UNITED STATES PATENT OFFICE.

RICHARD HEWITT, OF BRANDON, MANITOBA, CANADA, ASSIGNOR OF TWO-THIRDS TO
HECTOR COLIN McMARTIN, OF WINNIPEG, CANADA.

REGISTER.

960,548.

Specification of Letters Patent.

Patented June 7, 1910.

Application filed July 6, 1909. Serial No. 506,137.

To all whom it may concern:

Be it known that I, RICHARD HEWITT, of the city of Brandon, in the Province of Manitoba, Canada, have invented certain

5 new and useful Improvements in Registers, of which the following is the specification.
My invention relates to hot air registers, especially to that type which are inserted in the wall rather than in the floor of a

10 room.
The object of the invention is to provide a register the damper or vane of which is adapted to have a swinging motion around a pivotal point or a lateral motion within 15 the flue adjoining the register so that a more even distribution of hot air can be had between the lower and higher rooms of a building.

My invention consists essentially in a 20 frame having the usual ornamental grill, opposing supporting plates secured to the frame, a swinging crank rod or shaft carried by the plates, a damper or vane pivotally secured to the rod, means designed to 25 engage with the upper edge of the damper, and means for operating the rod, the parts being arranged and constructed as herein-after more particularly described.

Figure 1 is a front elevation of a form of 30 register embodying my invention and secured in position in the wall. Fig. 2 is a vertical sectional view through the register, the section being taken in the plane denoted by the line $X-X'$, and looking in the direction of the arrow a . Fig. 3 is a vertical sectional view through the register, the section being taken in the plane denoted by the line $X-X'$, Fig. 1, and looking in the direction of the arrow b . Fig. 4 is a rear view 35 of the register detached from the wall. Fig. 5 is a vertical sectional view corresponding to that shown in Fig. 3, the damper or vane appearing in a second position. Fig. 6 is a vertical sectional view corresponding to 40 that shown in Fig. 3, the vane or damper being shown in a third position.

In the drawings like characters of reference indicate corresponding parts in each figure.

50 1 represents the wall of a room which has the usual opening 2 therein which communicates between the air flue 3 and the interior of the room. The opening 2 is bounded by the usual wooden frame 4.

55 5 is the register frame which is inserted within and secured to the wooden frame 4,

said register frame having a flange 6 provided thereon to which flange there is secured the usual ornamental grill 7 by screws 8.

9 and 10 are plates or lugs secured firmly to the register frame by rivets 11, said plates being directly opposite and located toward the lower edge of the frame and at the interior side thereof.

12 is a crank rod having the cross or body portion thereof appearing at 13, the two extending ends 13' passing downwardly to the inner sides of the plates 9 and 10, respectively, where they are pivotally received, thereby allowing the rod to swing centered on bearings formed in the plates. The extremity 13² of one of the ends 13' is continued downwardly at the outer side of the plate 10 and is hooked, for a purpose later apparent.

14 is a damper or vane adapted to completely close the openings of the grill so that air is prevented from passing into the room when the damper is closed. The damper is 80 pivotally suspended on the cross or body portion of the rod by straps 15, the straps being attached to the damper somewhat below the upper edge thereof. The upper edge of the damper is hooked backwardly on itself at 16.

17 is a swivel secured centrally to the register frame at the top and having secured to its inner end a hooked bar 18 which is adapted in certain positions of the swivel 90 to engage with the upper edge of the damper.

19 is a bell crank pivotally secured at 20 to the inner side of the plate 10, said bell crank having one arm thereof projecting 95 at the side of the grill and appearing within the room where it is provided with a knob 21. The arm above referred to is provided with teeth which are adapted to pass within notches 22 located in the side of the grill. 100 In this way it is possible to set the bell crank in several positions.

23 is a link pivotally secured to the downwardly extending arm of the bell crank at 24 and having its other end connected with the hooked extremity 13² of the rod 12. The link 23 is provided with a series of openings 23' whereby it can be adjusted.

Although I have shown the upper edge of the damper hooked backwardly on itself it 110 will be understood that a hooked plate could be secured to the damper to fulfil the same

conditions as the hooked edge supplied, and it is further to be understood that any convenient way of holding the bell crank in the desired position may be used, as the particular manner in which this is done forms no part of my invention.

If it is desired to close the register and allow the hot air to pass upwardly in the flue 3, in the direction indicated by the arrow 10 it is only necessary to force the knob 21 downwardly to its limiting position. This throws the upper edge of the damper against the grill work and the action of the rod 12 closes the damper tightly against the inner 15 side of the grill. With the damper in this position it is possible to turn the swivel 17 so as to cause the hooked bar 18 to pass behind the hooked upper edge of the damper. If the knob 21 be then forced upwardly the 20 damper is caused to swing upwardly and backwardly within the flue, the limiting position being shown in Fig. 5. In this instance it will be seen that the damper swings on the hooked swivel. This position of the 25 damper will prevent warm air from passing upwardly within the flue.

If it be desired to have the hot air within the flue equally distributed to the lower and upper rooms one turns the swivel 17 so as to 30 throw it from behind the hooked upper edge of the damper and then raises the knob to its upper limiting position. This causes the damper to assume the position shown in Fig. 6. The damper in this position in no 35 way affects the circulation of air.

What I claim as my invention is:

1. In a register, the combination with a frame, a pivotally supported crank rod carried by the frame, a damper pivotally suspended from the crank rod, means for bodily displacing the damper, and means engageable with the upper edge of the damper when the damper is brought to closed position.

2. In a register, the combination with a frame, of a pivotally supported crank rod carried by the frame, a damper pivotally suspended from the crank rod, means for swinging the crank rod on its pivotal points 50 to bodily displace the damper, and means designed to engage with the upper edge of the damper when in its closed position.

3. In a register, the combination with the frame, of a pivotally supported damper carried by the frame, means for bodily displacing the damper, and means engageable with the damper and designed to convert the said

movement into a swinging movement around a pivotal point, as and for the purpose specified.

60

4. In a register, the combination with the register frame of a pivotally supported damper, means for bodily displacing the damper, and means carried by the frame and engageable with the damper whereby the said 65 movement is converted into a swinging movement around such engaging means; as and for the purpose specified.

5. In a register, the combination with a suitable frame, of opposing plates carried by the frame, a crank rod mounted in bearings formed in the plates, a damper pivotally suspended from the crank rod, means for swinging the crank rod, and swiveled means secured to the frame and engageable with 75 the upper edge of the damper when the damper is in the closed position, as and for the purpose specified.

6. In a register, the combination with a suitable frame, of opposing plates secured to the frame, a crank rod having the ends thereof mounted in bearings formed in the plates, one of the ends of the rod extending beyond the plate and having the extremity thereof hooked; a damper pivotally secured to the 85 rod by straps, a pivotally mounted bell crank linked with the hooked extremity of the rod, and a swivel carried by the frame and engageable with the upper edge of the damper, as and for the purpose specified. 90

7. In a register, the combination with a frame having a suitable opening therein receiving a grill, of a set of opposing plates secured to the frame and toward the lower side thereof, a crank rod pivotally mounted 95 in bearings carried by the plate, said rod having one of its ends extending beyond the adjoining plate and with the extremity hooked, a bell crank pivotally secured to said latter plate, a link secured to the bell 100 crank and adjustable to the hooked extremity of the rod, a damper pivotally suspended from the cross rod and having a hook formed at its upper edge, and a hooked swivel carried by the frame and adapted to 105 engage with the hook aforesaid formed on the damper when the damper is brought to the closed position.

Signed at Brandon in the Province of Manitoba, this 20th day of May 1909.

RICHARD HEWITT.

In the presence of:

ROSAMOND GARDINER,
HAROLD FORSHAW.
